UNITED STATES PATENT OFFICE.

CHARLES H. WHEELER, OF EAST PALESTINE, OHIO.

DESIGN FOR A RUBBER TIRE.

Application filed October 20, 1921. Serial No. 509,184. Term of patent 7 years.

To all whom it may concern:

Be it known that I, CHARLES H. WHEELER, a citizen of the United States, residing at East Palestine, in the county of Columbiana and State of Ohio, have invented a certain new, original, and ornamental Design for Rubber Tires; and I do hereby declare the following is a specification, reference being had to the accompanying drawing, forming a part thereof.

Figure 1 is a plan view of a segment of a tire showing my design;

Fig. 2 is a transverse section on the line 2—2 of Fig. 1.

I claim:

The ornamental design for a rubber tire, as shown.

In testimony whereof I affix my signature.

C. H. WHEELER.
